[57] CLAIM

The ornamental design for a paddleboat or the like, as shown and described.

DESCRIPTION

FIG. 1 is a top perspective view of a paddleboat or the like showing my new design;

FIG. 2 is a top plan view thereof;

FIG. 3 is a front elevational view thereof, the rear elevational view being a mirror image of that shown;

FIG. 4 is a side elevational view thereof, the opposite side elevational view being a mirror image of that shown;

FIG. 5 is a bottom plan view thereof.
